COOKING RANGE

George E. Dexter, Taunton, Mass., assignor to
 Glenwood Range Company, Taunton, Mass., a
 corporation of Massachusetts

Application November 2, 1934, Serial No. 751,166

5 Claims. (Cl. 126—39)

The invention relates to improvement in cooking ranges and pertains especially to an improved means for closing the front end of the compartment or chamber which contains the top burners together with their manifold and valvular connections.

The essential object of the invention is to provide an improved type of door for this closure with arrangement whereby the door when closed will conceal the handles of the valves and occupy a position substantially flush with the face of the range, and when open will turn into an out-of-the-way position free from the front and top of the range providing accessibility to the handles of the valves or other controlling members normally concealed by the closed door.

Further objects of the invention include an arrangement whereby the manifold and valvular connections, the handles of the valves excepted, will lie concealed at all times from the front of the range, also an arrangement whereby indrawn secondary air will be permitted free entry to the top burners when the door is open and the burners are in operation, and the indrawn air will assist in keeping the door cool and untarnished by heat from the burners.

The invention can best be seen and understood by reference to the drawings in which.

Fig. 1 is a perspective of the range with all doors closed.

Fig. 2 is a perspective of the top of the range cut away to show the parts for enclosing the fore end of the top burner chamber to which the invention essentially pertains.

Figs. 3 and 4 are cross sections of the top burner chamber, Fig. 3 showing the door which closes the fore end of this chamber in a closed position, and Fig. 4 the position of the door when open.

Fig. 5 is a perspective of the door and sliding frame to which the door is hinged, as will later be described.

Fig. 6 is a cross section of the top burner chamber showing especially the sliding frame and ways on which this frame is arranged to slide; and

Fig. 7 shows in perspective a detail of construction to which special reference will later be made.

Referring to the drawings, 1 represents the top burner compartment having a bottom 2, side walls 3, 3, respectively, end wall 4, and a top 5. That portion of the top lying above the burners is cut away to contain an open grid (not shown) and is closed by a cover 6 as is now

quite customary in ranges of this type. 7 represents the burners, 8 the manifold, 9 the valves, and 10 the handles of the valves. 11 is the pan resting on the bottom of the compartment beneath the burners.

Arranged in the fore part of the compartment 1 between the side walls 3, 3 thereof is a panel 12. The handles 10 to the valves lie outside this panel so as to be accessible from the front of the range. They connect with the valves 10 through openings 13 in the panel. The panel, however, normally conceals the manifold and valves from the front of the range. The panel is spaced from the bottom 2 of the compartment, its extension only being such as will enable it 15 to conceal the manifold and valves as aforesaid, but will leave ample space 14 between its bottom edge and the bottom of the compartment to permit of a free entry of secondary air to the top burners when these burners are in operation. 20

The open front end of the compartment 1 is closed by a door 15. The door when closed occupies a position substantially flush with the front of the range, assisting in the finish thereof and, accordingly, will lie outside of the panel 12 25 and handles 10 of the valves, concealing them. The door, generally rectangular in form, is preferably made of metal plate with flanged edges 16 all around, thereby permitting the door to fit over the handles for when the door is closed the 30 handles lie at least in part within the enclosure formed by its flanged edges. The closed position of the door is defined by the flanged edges thereof at either side of the door bearing against the ends 17 of the panel 12, the body of the 35 panel being preferably slightly inset with relation to its ends. The closed position of the door is further defined by the bearing of its bottom flanged edge against a strip 18 on the bottom of the compartment 1 just forward of the front 40 end of the pan 11 resting on this bottom.

The door is hingedly mounted on a sliding frame 20. This frame, generally rectangular in form, comprises side bars 21, a front end bar 22, a rear end bar 23, and an intermediate cross-bar 24. The door is preferably hinged as shown to the side bars 21 of the frame. These side bars, extending beneath the front end bar 22 and beyond the same, are provided each with an angular piece 25 preferably welded thereto which 50 presents a turned lip or flange 26 lying in a plane substantially parallel with the side of the door.

Fixed to the door, preferably by welding, at each bottom inside corner of the door, is an 55

angularly bent metal strap 27 with bent portions spaced from and parallel with the side and bottom flanges of the door. Those portions of the straps which lie spaced from and parallel with the side flanges of the door lie parallel and flush with the flanges 26 on the side bars of the sliding frame, and hinge connection is made between the flanges 26 and plates 27 by means of pins or rivets 28 passed through them. (See Fig. 7.)

Thus the door is hinged to the sliding frame 20 whereby it may occupy either an upright position at right angles to the frame or a downturned open position substantially parallel with the frame. Inasmuch as the hinge connections lie above the bottom of the door, when the door is occupying a position at right angles to the frame the side flanges 16 of the door below its hinge connections will bear against the ends of the side bars 21 of the sliding frame which then assist in maintaining the door in its upright position. When the door is turned to an open position substantially parallel with the sliding frame upon which it is mounted, the side flanges 16 of the door will engage and rest upon the tops of the side bars 21 of the sliding frame.

The frame 20 is mounted to slide in or out of the compartment 1 by ways 30 arranged therein. These ways preferably consist of rounded metal strips fixed to the bottom 2 of the compartment exteriorly adjacent the opposite sides of the pan 11 resting on said bottom. The frame 20 is provided with members slidable upon these ways and these members are preferably made by extending the metal of the side bars 21 to form rounded members 31 which fit telescopically over the respective ways 30 and are slidable thereon.

The door thus mounted, when turned to occupy a position at right angles to the sliding frame or slide, may be brought into a proper closed position with relation to the open end of the compartment 1, as shown in Fig. 3, simply by moving in the slide. For opening the door the slide is first drawn out, carrying the door with it. When the slide has been withdrawn sufficiently to permit of the door being turned inwardly, the door is turned down to lie substantially parallel with the slide resting thereon as aforesaid. Thereupon the slide may be moved inwardly, carrying the door with it. The door will enter the space 14 below the panel 12, and when the slide has been moved completely in the door will occupy a position lying below the panel 12 and above the pan, with extension into the fore end of the compartment 1, as shown in Fig. 4, although the extension of the door will not be so far that drip from the burners will fall upon it. The bottom of the door will lie about flush with the front of the range. The return of the door to a closed position is obtained simply by a reverse operation. The slide is drawn out, the door then turned up to an upright vertical position with relation to the slide, and the slide then moved in for closing the door.

Thus the closed and open positions of the door are obtained simply by moving the slide 20 in or out. This operation is facilitated by a handle 32 on the door.

The ways 30 and frame members 31 slidable thereon are preferably made of some considerable length in order that they may maintain their bearing as the frame is slidably moved and prevent binding.

When the door is open ample supply of secondary air may then be indrawn to pass by way

of the space or opening 14 below the panel to the burners. This indrawn air will act to keep the door cool and untarnished by heat from the burners when the burners are in operation.

When the door is open the pan 11 is then accessible and may be drawn out as occasion may require. 5

I claim:

1. In a cooking range having a compartment for heating units provided with an open end, a door for closing said end, a slide withdrawable outwardly beyond said open end of the compartment and upon which slide the door is mounted to occupy a closed position when the slide is in, or be withdrawn outwardly away from its closed position when the slide is out, and means for hingedly mounting the door on said slide whereby the door, when withdrawn as aforesaid, may be folded inwardly on the slide, to occupy a downturned open position, and the door thence be carried by the slide into said compartment on moving the slide in.

2. In a cooking range having a compartment for heating units provided with an open end, and a panel inwardly removed from said open end of the compartment and spaced from the bottom of the compartment, a door for closing said end, a slide arranged beneath said panel withdrawable outwardly beyond said open end of the compartment, and upon which slide the door is mounted to occupy a closed position when the slide is in, or be withdrawn outwardly away from its closed position when the slide is out, and means for hingedly mounting the door on said slide whereby the door, when withdrawn as aforesaid, may be folded inwardly on the slide to occupy a downturned open position, and the door thence be carried by the slide into said compartment to occupy a position beneath said panel on moving the slide in. 40

3. In a cooking range having a compartment for heating units provided with an open end, a door for closing said end, a slide arranged above the bottom of said compartment and withdrawable outwardly beyond said open end thereof, and upon which slide the door is mounted to occupy a closed position when the slide is in, or be withdrawn outwardly from its closed position when the slide is out, ways above the bottom of the compartment on which the slide is movable, and means for hingedly mounting the door on said slide comprising a hinge connection between the end of the slide and the door with location above the bottom of the door whereby the door, when withdrawn as aforesaid, may be folded inwardly on the slide to occupy a downturned open position, and the door thence be carried by the slide into said compartment on moving the slide in. 45

4. In a cooking range having a compartment for heating units provided with an open end and a pan at the bottom of said compartment removable through said open end, a door for closing said end, a slide arranged above the pan withdrawable outwardly beyond said open end of the compartment and upon which slide the door is mounted to occupy a closed position when the slide is in, or be withdrawn outwardly away from its closed position when the slide is out, and means for hingedly mounting the door on said slide whereby the door, when withdrawn as aforesaid, may be folded inwardly on the slide to occupy a downturned open position, and the door thence be carried by the slide into said compartment 60

partment to occupy a position above said pan on moving the slide in.

5. In a cooking range having a compartment for heating units provided with an open end, a panel inwardly removed from said open end of the compartment and spaced from the bottom of the compartment, and a pan at the bottom of the compartment removable through said open end thereof, a door for closing said end, a slide arranged above the pan and withdrawable outwardly beyond said open end of the compartment, and upon which slide the door is mounted to occupy a closed position when the slide is in, or be withdrawn outwardly from its closed

5 position when the slide is out, ways adjacent the opposite sides of said pan above the bottom of the compartment on which the slide is movable, and means for hingedly mounting the door on said slide comprising a hinge connection between the end of the slide and the door with location above the bottom of the door whereby the door, when withdrawn as aforesaid, may be folded inwardly on the slide to occupy a downturned open position, and the door thence be carried by the 10 slide into said compartment to occupy a position beneath said panel and above said pan on moving the slide in.

GEORGE E. DEXTER.
